WELL DEVICE

Robert Roy MacGregor, Long Beach, Calif., assignor, by mesne assignments, of one-third to Orvel C. Slavens, one-third to Laurence B. MacGregor, and one-third to Robert Roy MacGregor, all of Long Beach, Calif.

Application July 25, 1938, Serial No. 221,128

5 Claims. (Cl. 166—18)

This invention relates to well devices, and particularly to a form of brush adapted to effectively clean liners, and the like.

The present invention has been found in actual practice to readily clean the perforations of liners, removing all sediment of every character so that non-producing wells, which would produce otherwise if the oil was permitted to enter the liner, may have production reestablished.

10 An object of the invention is the provision of a device which is so constructed as to readily withstand abuse, hard usage, and still perform excellent services in the scraping and cleaning of well tubing and the like.

15 Another object of the invention resides in the novel construction of a well cleaner, whereby the main cleaning elements may be readily and inexpensively removed and new ones substituted, which does not require skilled labor for the said removal and renewal of such elements, and which as to cost of manufacture is superior to devices for the purpose of cleaning tubing, casing, and the like.

20 In the practice of the invention, I have provided a plurality of wires carried by a cylindrical body, the wires of which project radially from the body and in a spiral arrangement, whereby the wires are assured of contacting every portion of a tubing or casing within which the said tool is received, thus assuring that a proper 25 cleaning of the tubing or casing results. Furthermore, the tool is so constructed that the insertion of said tool with its wires within a tubing or casing does not break the wires but permits 30 the wires to readily move radially when given the opportunity, such as upon reaching any perforated area of the tubing or casing.

35 In actual practice, it has been found that a device of the character about to be disclosed may 40 be inserted within a well hole through the medium of a wire line, and after a few hours of working the tool, that the casing or tubing will readily remove all wax, asphalt, and deleterious substances of all kinds so that a non-producing 45 well has its production reestablished or increased production will result.

The invention includes among its objects a device which is inexpensive in cost of manufacture, easily assembled, and superior as to results 50 obtained.

55 With the above mentioned and other objects in view, the invention consists in the novel and useful provision, formation, construction, association, and relative arrangement of parts, members and features, all as shown in certain em-

bodiments in the accompanying drawings, described generally, and more particularly pointed out in the claims.

In the drawings:

Figure 1 is a fragmentary elevation of the improved tool as an entirety,

Figure 2 is an elevation of the tool in slightly modified form,

Figure 3 is a sectional view on the line 3—3 of Figure 1,

Figure 4 is a sectional view on the line 4—4 of Figure 1, and,

Figures 5, 6, 7 and 8 are elevations, partly in vertical section and fragmentary, illustrating the operation incident to the insertion of wire members between two elements of the invention for the purpose of securing said wire members in position to said elements.

Referring now with particularity to the drawings, I have shown in Figure 1 a complete embodiment of my invention and which I herein designate 1. A modified form of the invention is shown in Figure 2 and designated as an entirety by 2. Both devices 1 and 2 operate on the same principle so far as action of the instrumentalities is concerned, save and except that that form of the invention 2 is capable of negotiating tortuous paths. In this respect, the instrumentality 2 has articulated members for the purpose named aforesaid.

The instrumentality 1, so far as separate components thereof are concerned, includes a mandrel or pull rod 3, a sleeve or body 4 surrounding the mandrel, and brush members 5 locked between the mandrel and the sleeve or body and radially or tangentially extended outwardly from the periphery of said sleeve or body for a given area or length thereof.

Slidably fitted upon the sleeve or body are spring guide members 6 and 7, the brush members being interposed therebetween. The spring guide members in both instances are of identical construction, both including spaced apart rings 8 and 9 surrounding the sleeve or body with bowed leaf springs 10 spacedly secured between said rings. The body or sleeve is threaded adjacent one end 11 and there is secured to this end 11 a member 12, which includes a box 13 for threaded engagement with 11, a squared area 14 whereby the member 12 may be manipulated or rotated 15. Adapted to be secured to the pin 15 is a member 16 having a box 17 and a bail 18.

Referring to Figure 4, it will be observed that the mandrel is threaded at 19 to receive a nut 55

20. The purpose of this nut is to secure adjustment between the mandrel and the body when the wires are in position between the mandrel and body. To complete the device, a 5 round headed cap nut 21 is threaded to the sleeve at 22.

Referring now to Figures 5 to 8, inclusive, I preferably so position the mandrel relative to the sleeve that a plurality of diametric bores may be 10 formed in both said members, the bores being adapted to align under certain conditions. To effectively provide for such bore alignment, I have provided adjacent one end of both the sleeve and mandrel, bores 23 and 24, and these bores 15 when aligned as shown in Figure 5, may have received therein a pilot pin 25, see Figure 6. This pilot pin positions the sleeve and mandrel so that the openings adapted to receive the wire brushes may be readily formed by drilling or otherwise.

20 As stated, I may form the bores in the mandrel and sleeve in any direction desired; however, assuming for the instant that all of said bores are radial, for a given length of said sleeve and mandrel, the bores are of the same diameter, as indicated in Figure 6 at 26 and 27. In each instance, I preferably form the bores so that the bores are of a slightly greater diameter than the bunched diameter of the wires forming the individual brushes, as shown in Figure 7. In Figures 7 and 30 8, it will be observed that a given area of the drilled openings of the sleeve are reamed, thereby making holes greater in diameter than the diameter of the openings 26 of the mandrel, as indicated at 28.

35 In the drilling of the various openings of both the sleeve and body, and particularly when the sleeve and body have been locked in a definite position by the pilot pin, I preferably so form the bores that after the wire brushes are received therein, that a wire brush area from top to bottom defines a spiral, which in the present instance forms a quarter turn on the sleeve. See Figure 1 and the brushes shown at 29, 30, 31, 32, 33, 34 and 35.

40 45 That form of the invention shown in Figure 2 differs, as has previously been stated, from the form shown in Figure 1 in that the same is articulated. Specifically, one articulation is shown at 50. Articulation is accomplished by providing one or more series of swivelly connected brush carrying sleeves and mandrels. Thus, in Figure 2, one section 51 includes the tubular sleeve 52, within which is a mandrel 53. In order to drill holes either radially, tangentially, or otherwise, through both the mandrel and the sleeve, I have provided at 54 a pilot pin opening and at 55 is a drilled opening in the mandrel, whereby when the pilot pin openings are in alignment and the pilot pin inserted within 50 55 said openings, the holes for receiving the brushes are in alignment. The mandrel 53 is formed with a threaded area 56 and a reduced diameter threaded portion 51. An adjusting nut 58 is carried on the threads 56, this nut abutting against an end of the sleeve 52 so that the mandrel may be forcibly moved in one direction relative to the sleeve. A ball 59 is provided with a threaded opening for threaded engagement with 57.

60 65 70 The second section 60 of the device includes, as before, the mandrel 61 and sleeve 62, the sleeve in this instance being internally threaded at 63 to receive a threaded nut 64. This threaded nut has an enlarged diameter portion which is threaded at 65 to receive a socket nut 66. In

this regard, it is to be observed that the end 67 of the nut 64 is curved so as to conform to the curvature of the ball 59. This construction affords what may be termed a ball and socket arrangement. The section 60 is similar in construction to that shown in Figures 5 to 8, inclusive. 5

The operation, uses and advantages of the invention just described are as follows:

Viewing Figure 6, it will be seen that the openings adapted to receive the brushes 5 are in alignment. These brushes are preferably formed of a plurality of spring wires. The spring wires are inserted through the aligned openings of the mandrel and the sleeve, and after being properly positioned so that end lengths thereof extend substantially equal distances from the periphery of the sleeve, the brushes are locked in working relationship with the sleeve and mandrel. This is accomplished by removing the pilot pin 25 and then, in the case of the form of the invention depicted in Figure 1, rotating the nut 20 (see Figures 4, 7 and 8) so that the mandrel is forcibly moved outwardly of the sleeve. This forcible movement will cause the brushes to be clamped 25 between the mandrel and the sleeve, as illustrated in Figure 8 at 70, 71, 72 and 73. Thus, the mandrel is placed in tension and the sleeve in compression.

In order that there should be an equal gripping action upon all of the brushes by the mandrel and sleeve, it has been found necessary to ream the holes at certain portions of the sleeve. As a rule, a large number of brushes are utilized and the clamping action that occurs against each brush when the mandrel is moved relative to the sleeve is such as to substantially occur in a progressive manner. Hence, it will be recognized upon viewing Figure 7 that the brush at 74 will actually move a greater distance than the brush 40 at 75 confined at another zone of the device. Adjacent the top of the device, and viewing Figure 1 with its bail, the bail being considered the top portion, the drilled openings of the mandrel and the sleeve conform more as to diameter than do 45 those openings from the central zone downwardly of the device. The construction is such that substantially equal gripping is effected upon the wire brushes from top to bottom.

The same procedure of alignment of openings, the insertion of the brush members, and the like, occurs for that form of the device shown in Figure 2.

When it is desired to operate the tool, the same may be lowered in any approved manner within well tubing or casing by a wire line or other instrumentality, a wire line being shown at 90. If it is desired to scrape the interior of the tubing or casing, the device may be of sufficient weight to drop within the tubing or casing, and then by moving the same upwardly or downwardly within the tubing or casing, properly clean the walls thereof.

The device effectively cleans perforations in a liner for the reason that the wires will pass easily 65 through said perforations, and movement upwardly and downwardly of the said device will break up and "brush out," as it were, all deleterious material that in any manner closes the perforations.

A tool of the character described may be of considerable length and it is sometimes advisable, if the tubing becomes bent, to use the articulated form shown in Figure 2 so that the device will not bind within the tubing. 75

After the device has been run and removed from the tubing or casing, an operator may examine the brushes and if any of the brushes have been worn to a considerable extent or bent so as to render the same non-usable, the brushes may be easily removed and new ones inserted through the simple expedient of turning the adjusting nut 20 or 58 so as to release the gripping action that occurs upon said brushes between the mandrel and the sleeve, and inserting new brushes. It will be seen that the only parts likely to wear in the device are the brushes, and that these brushes are of very simple construction consisting, as shown, of elongated bunches of flexible wire adapted to be clamped or locked in a given position between the mandrel and the sleeve. Thus, any replacement, means replacement of brushes only, an item of small expense.

The leaf springs 10 aid in guiding the tool as it enters either the casing or tubing in its downward movement, and during reciprocation of the tool to perform a cleaning action. To limit movement of the leaf springs 10 in one direction, I have provided stop collars 91. In this manner, the leaf spring collars 9 are prevented from damaging the brushes 5.

Furthermore, the spiral arrangement of the brushes assures that the brushes will contact all of the interior surface of the tubing or casing during reciprocation of the tool.

It is obvious that various changes and modifications and variations may be made in practicing the invention in departure from the particular embodiments of the invention shown herein, without, however, departing from the true spirit thereof.

I claim:

1. A device adapted to clean well tubing, casing liners and the like, comprising a sleeve, a mandrel received within said sleeve, said mandrel and sleeve being provided with registerable openings extending therethrough, flexible wire brush forming elements extending through said openings and extending from spaced points of said sleeve, means for temporarily locking said sleeve and mandrel with their openings in coaxial relationship to permit adjustment of said brush forming elements, and means to shift said mandrel with respect to said sleeve to lock said brush forming elements in position.

2. A well device for cleaning tubing, casing liners, and the like, comprising an articulated body, brush members extended from the periphery of said body in a spiral arrangement, guide members positioned on said body above and be-

low the brush members for centering and guiding said body and brush members as the device is reciprocated, and means for reciprocating the device in a tube, casing liner, and the like.

3. A well device for cleaning tubing, casing liners, and the like, comprising an articulated body, wire brush members extended from the periphery of said body in a spiral arrangement, guide members positioned on said body above and below the brush members for centering and guiding said body and brush members as the device is reciprocated, and means secured to the body whereby the tool may be reciprocated within a casing, tubing, liner, or the like.

4. In a well device of the character disclosed, 15 a mandrel, a sleeve surrounding said mandrel, said sleeve and mandrel formed with diametrical openings adapted to be in registry when the mandrel and sleeve are in one position, said diametrical openings being arranged longitudinally of the 20 sleeve and mandrel, and said openings adapted to receive brush members; certain of said openings in the sleeve being of greater diameter than the corresponding openings in the mandrel, whereby 25 all of said brush members are held under substantially the same gripping pressure when the sleeve is moved in one direction relative to the mandrel to bring the openings of said sleeve and mandrel out of registry.

5. A device for cleaning a well tubing, casing liner, and the like, including a mandrel and a sleeve slidable on said mandrel, said mandrel and said sleeve being provided with openings, a removable pin cooperable with registerable apertures in said sleeve and mandrel for holding said sleeve in position on said mandrel with said openings in said sleeve in alignment with the corresponding openings in said mandrel, brush bristles inserted through the aligned openings in said sleeve and said mandrel with the ends of said 40 bristles extending beyond the periphery of said sleeve, said openings being arranged to grip said bristles substantially uniformly when the parts are in clamped relationship, the lower end of said mandrel being threaded and extending 45 below the lower end of said sleeve, and a nut on said threaded lower end of said mandrel for engaging the lower end of said sleeve for drawing said mandrel downwardly in clamped relationship 50 with respect to said sleeve, when said alignment means is released, for gripping said bristles in said openings between said sleeve and said mandrel.

ROBERT ROY MACGREGOR. 55
